VACUUM CLEANER

Tord Erik Daniel Bilde and Anders Eriksson-Jons, Stockholm, Sweden, assignors to Electrolux Corporation, Dover, Del., a corporation of Delaware

Application December 15, 1932, Serial No. 647,344
In Germany December 24, 1931

6 Claims. (Cl. 183—57)

Our invention relates to vacuum cleaners and particularly to vacuum cleaners of the enclosed dust bag type. One of the objects of our invention is to provide means for regenerating or 5 cleaning a dust bag or other dust separating member by flow of air without removing it from the cleaner. A further object is to accomplish this without removing the accumulated dirt from the cleaner.

10 Further objects and advantages of our invention will be apparent from the following description thereof considered in connection with the accompanying drawings which are to be considered as forming part of this specification and of 15 which:

Fig. 1 is a cross-sectional view of one embodiment of our invention;

Fig. 2 is a cross-sectional view taken on the line 2—2 of Fig. 1;

20 Fig. 3 is a top view of a portion of the cleaner shown in Fig. 1;

Fig. 4 is a cross-sectional view taken on the line 4—4 of Fig. 1;

Fig. 5 is a cross-sectional view taken on the line 25 5—5 of Fig. 4;

Fig. 6 is a view similar to Fig. 4, but with certain of the parts in a different relative position;

Fig. 7 is a cross-sectional view taken on the line 30 7—7 of Fig. 6;

Fig. 8 is a cross-sectional view similar to Figs. 4 and 6, but with certain of the parts in still different relative positions; and

Fig. 9 is a cross-sectional view taken on the line 35 9—9 of Fig. 8.

Referring more particularly to Fig. 1, reference character 40 designates a base member which is supported by a caster or pivoted wheel 41 and two small wheels 42. Base member 40 carries a motor support 43 upon which is suitably mounted an electric motor 44. A centrifugal fan 45 is mounted on the armature shaft 46 of the motor. A wall 47 forms the bottom of the fan chamber which is provided with an outlet opening 48. The inlet to the fan chamber is through the circular 45 opening 49 in the motor support member 43.

Suitably secured to member 43 is an upright cylindrical drum 50. The upper end of drum 50 is formed as a flange 51. An annular member 52 provided with a packing 53 is adapted to seat on flange 51. Member 52 is formed with a down-turned flange 54 to which is suitably secured the open mouth of a bag shaped dust separating member 55. Openings 52a are formed in member 55, as may be seen in Figs. 1 and 2. Member 55 is so formed as to extend downwardly close to

the bottom of the air-tight casing formed, in part, by the barrel 50 and motor support 43 and then to be folded back upon itself so as to form an annular dust collecting chamber 56. A ring 57 placed at the bottom of chamber 56 serves to hold the dust separating member in this position. The more central portion of member 55 is supported by a ring 58 secured to the top of motor 44.

Annular member 52 is held in place on flange 10 51 by means of a cover member 59 which is held in place by suitable fastening clamps 60. Cover member 59, barrel 50, motor support 43 and the housing of motor 44 comprise an air-tight casing.

Cover member 59 comprises an outer annular 15 part 59a and an inner circular plate 59b. An intermediate wall member 61 is resiliently supported by plate 59b of cover member 59 by means of bolts 62 and springs 63. Intermediate wall 61 is provided with a downwardly extending conduit 20 64 and an opening 65. Opening 65 and conduit 64 are disposed on radii of plate 59b which are preferably at right angles to each other, as may be seen in Figs. 3, 4, 6 and 8. An annular extension 66 is carried by wall 61 and its outer periphery carries a packing member 67 which is adapted to seat against member 52 when the cover 59 is put in place. The extension 66 also carries a dust separating member 68 which may be made of cloth and which is provided with an opening 25 30 somewhat offset from the middle through which extends conduit 64. Member 68 is suitably secured to member 66. It will thus be seen that intermediate wall 61, extension 66 and dust separating member 68 form an intermediate chamber 35 61a which has communication with the space above it through the opening 65. It will also be noted that dust separating members 55 and 68 together comprise a dust bag, the member 55 being the lower portion of the bag and the member 40 68 being the upper portion.

Plate 59b is provided with a centrally disposed opening 69 in which is journaled a valve member 10. To the top of valve member 10 is secured an inlet connection 71 which is adapted to be connected to a hose leading to a suitable cleaning implement. A handle 72 is pivoted to a collar 73 which is secured to valve member 10 by means of a set screw or the like 74. Handle 72 is provided with a projection 75 which is adapted to engage recesses formed in plate 59b so that, when the handle is in a substantially horizontal position, as shown in Fig. 1, the valve member cannot be rotated. In order to move the valve member, handle 72 is pivoted to the position shown in 55

Fig. 7, in which position projection 78 is withdrawn from the recess and the handle, collar and valve may be rotated in a horizontal plane.

5 Valve member 70 preferably is formed as a single casting. The casting is formed with a passageway 76 which is in communication with inlet member 71 for all positions of the valve. The upper end of passage 76 is centrally disposed with 10 relation to the axis of rotation of the valve while the lower end of the passage is displaced to one side of the axis. The arrangement is such that, with the valve in the position shown in Figs. 1, 3, and 4, the lower end of passage 76 is in alignment with conduit 64 leading into the interior of 15 the dust bag. The valve member is also provided with an upper flange 77 which preferably has a machined surface adapted to form a substantially air-tight seal with the plate 59b. Flange 77 has the configuration shown in Figs. 3, 4, 6, and 8. 20 In the position shown in Figs. 1, 3, 4, and 5, flange 77 covers an opening 78 formed in cover member 59 directly above opening 65 in intermediate wall 61. The valve is also formed with a lower flange 79 having a configuration as shown in Fig. 4. In 25 the position of the valve now being considered, flange 78 does not cover opening 65 in the intermediate wall 61, wherefore communication is established between intermediate chamber 61a and the space in the casing outside chamber 61a. 30 The upper and lower surfaces of valve 70, including flanges 77 and 79, preferably are machined, as are the adjacent surfaces of plate 59a and wall 61. Springs 63 force wall 61 against the valve member, which is in turn forced against 35 plate 59b, the machined surfaces providing a substantially air-tight fit between these members.

40 When the fan 45 is rotated with the valve in the above described position, air is drawn in through inlet 71, passage 76 and conduit 64 to the interior of the dust bag. The air passes through the upper portion 68 of the dust bag into intermediate chamber 61a and through opening 65 in wall 61 to the space within cover member 59. This air then passes through openings 52a to the 45 space within the casing outside of the lower portion of the dust bag. Air also passes through the lower portion 55 of the dust bag. The dust drawn in with the air is deposited for a greater part in the lower part of the dust bag, particularly in annular chamber 56. A portion of the 50 dust adheres to both the upper portion 68 and the upper part of the lower portion 55 of the dust bag. The air is withdrawn from the casing by fan 45 through opening 49 and is discharged from the fan through outlet opening 48.

55 When it is desired to clean the upper portion 68 of the dust bag, valve member 70 is rotated 90° to the position shown in Figs. 6 and 7. In this position the lower end of passage 76 of the 60 valve is in alignment with opening 65 in intermediate wall 61 and opening 78 in plate 59b is still closed by flange 77. Upon rotation of the 65 fan, air is drawn in through inlet opening 71, passage 76 and opening 65 into the intermediate chamber 61a. This air is then drawn through the upper portion 68 of the dust separating member into the interior of the dust bag. It will be seen that this air passes through member 68 in a reverse direction and thus dislodges dirt which 70 has adhered to the under surface of the member. This air passes out of the dust bag through the upper part of the lower portion 55 thereof and is discharged by the fan through outlet 48. During the above described operation the cleaning implement should be held in such a position that no

dust or dirt will be drawn in with the air inasmuch as any dirt so drawn in will be deposited on the upper side of dust separating member 68, which of course is undesirable. If desired, the 5 hose may be disconnected from inlet member 71 so that it is assured that the air drawn in is clean.

If it is inconvenient to draw clean air into the inlet 71, the dust separating member 68 may be regenerated by rotating the valve member 180° 10 from the position shown in Figs. 1, 3, 4 and 5. The valve member will then be in the position shown in Figs. 8 and 9. The valve member is provided with an additional passageway 80. In the position of the valve now under discussion 15 passageway 80 connects opening 78 in cover member 59 with opening 65 in intermediate wall 61. In this position, the lower end of passage 76 is closed by wall 61. When the fan is rotated, air is drawn in through opening 78, passage 80 and 20 opening 65 to the intermediate chamber 61a and passes from there through the upper portion 68 of the dust bag into the interior of the bag, thus dislodging any dirt adhering thereto. This air passes out of the dust bag through the lower portion 25 and is discharged by the fan through opening 48.

In the position of the valve shown in Figs. 1, 3, 4 and 5, passageway 80 is blanked off at the upper 30 end by plate 59b, and at the lower end by intermediate wall 61. In the position of the valve illustrated in Figs. 6 and 7, the lower end of passage 80 is in alignment with conduit 64 but the upper end of the passage is blanked off by cover member 59. In both of these last two positions 35 the passage 80 performs no function.

40 It will thus be seen that, in the embodiment of our invention herein described we have provided means for cleaning or regenerating a dust separating member by causing air to pass therethrough in a reverse direction with respect to the normal operating direction. In order to accomplish this cleaning or regenerating, it is only necessary to shift a valve member and it is not necessary to dismantle the cleaner or to alter 45 any hose connections thereto. Of course, when the bag become sufficiently filled with dust it is necessary to empty it, which may be done by removing cover 59 by unfastening members 60, whereupon the cover member may be lifted off the 50 barrel 50. Inasmuch as dust separating member 68 is carried by the cover member 59 it will be removed with it. Ring 52 will then be lifted from flange 51 and the lower portion of the dust bag withdrawn from the barrel and emptied. 55

While we have shown and described a more or less specific embodiment of our invention, it is to be understood that modifications thereof fall within its scope, which is to be limited only by the appended claims considered in the light 60 of the prior art.

What we claim is:

1. In a vacuum cleaner, an air-tight casing, a dust bag within said casing having a lower wall portion of pervious material and an upper wall 65 portion of pervious material, walls forming a chamber bounded in part by said upper portion, said casing formed with an inlet, means for passing air through said casing, and valve means for selectively connecting said inlet with the interior of said dust bag so that the air will pass out through the pervious upper and lower wall portions in parallel and for connecting said inlet with the interior of said chamber so that the air will pass into said dust bag through said upper 70 portion.

- wall portion and out of said bag through said lower wall portion.
2. The combination with a vacuum cleaner having an air-tight casing provided with an inlet connection, means for producing flow of air through said casing, and a bag shaped dust separating member therein, of means for cleaning a portion of said member comprising a wall forming with said portion a chamber within said casing, 5 said wall formed with an opening, a conduit communicating with the interior of said bag shaped member, and a movable valve member having a plurality of operative positions and so formed that in one of said positions communication is established between said inlet connection and said opening and said conduit is closed.
- 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710
2. The combination with a vacuum cleaner having an air-tight casing provided with an inlet connection, means for producing flow of air through said casing, and a bag shaped dust separating member therein, of means for cleaning a portion of said member comprising a wall forming with said portion a chamber within said casing, said wall formed with an opening, a conduit communicating with the interior of said bag shaped member, said casing being formed with an opening to the atmosphere, and a movable valve member having a plurality of operative positions and so formed that in one of said positions communication is established between said inlet connection and said conduit, the opening in said wall is open and the opening in said casing is closed, and in another of said positions said openings are in communication with each other, and said conduit is closed.
3. The combination with a vacuum cleaner having an air-tight casing provided with an inlet connection, means for producing flow of air through said casing and a bag shaped dust separating member therein, of means for cleaning a portion of said member comprising a wall forming with said portion a chamber within said casing, said wall formed with an opening, a conduit communicating with the interior of said bag shaped member, said casing being formed with an opening to the atmosphere, and a movable valve member having a plurality of operative positions and so formed that in one of said positions communication is established between said inlet connection and said conduit, the opening in said wall is open and the opening in said casing is closed, and in another of said positions said openings are in communication with each other, and said conduit is closed.
4. The combination with a vacuum cleaner having an air-tight casing provided with an inlet connection, means for producing flow of air through said casing and a bag shaped dust separating member therein, of means for cleaning a portion of said member comprising a wall forming with said portion a chamber within said casing, said wall formed with an opening, a conduit communicating with the interior of said bag shaped member, said casing being formed with an opening to the atmosphere, and a movable valve member having a plurality of operative positions and so formed that in one of said positions communication is established between said inlet connection and said conduit, the opening in said wall is open and the opening in said casing is closed, and in another of said positions said openings are in communication with each other, and said conduit is closed.
5. The combination with a vacuum cleaner having an air-tight casing provided with an inlet connection, means for producing flow of air through said casing, and a bag shaped dust separating member therein, of means for cleaning a portion of said member comprising a wall forming with said portion a chamber within said casing, said wall formed with an opening, a conduit communicating with the interior of said bag shaped member, said casing being formed with an opening to the atmosphere, and a movable valve member formed with first and second passageways therethrough and with upper and lower flanges, said valve member having three operative positions and so arranged that in the first position said first passageway establishes communication between said inlet connection and said conduit, said opening in said wall is open and said upper flange closes the opening in said casing, in the second position said first passageway establishes communication between said inlet connection and the opening in said wall, said upper flange closes the opening in said casing and said conduit is in communication with the second passageway which leads to and is closed by the casing wall, and in the third position said second passageway establishes communication between the opening in said casing and the opening in said wall, said conduit is closed by said lower flange and said first passageway is blanked off against said wall.
6. In a vacuum cleaner, an air-tight casing, a dust bag within said casing having a first wall portion of pervious material and a second wall portion of pervious material, walls forming a chamber bounded in part by said second portion, said casing formed with an inlet, means for passing air through said casing, and valve means for selectively connecting said inlet with the interior of said dust bag so that the air will pass out through the pervious first and second wall portions in parallel and for connecting said inlet with the interior of said chamber so that the air will pass into said dust bag through said second portion and out of said bag through said first portion.
